CLAIM

The ornamental design for a pop-up toy, as shown and described.

DESCRIPTION

FIG. 1 is a front perspective view of a pop-up toy, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1; and,

FIG. 11 is an enlarged detail view of area 11 in FIG. 2.

The broken lines in the drawings illustrate the portions of the pop-up toy, which form no part of the claimed design.

The dash-dot-dash broken lines illustrate the periphery of the enlarged views of the pop-up toy and form no part of the claimed design.

1 Claim, 11 Drawing Sheets
